C. H. PRAY.

FIRE ESCAPE.

APPLICATION FILED SEPT. 4, 1919.

1,343,642.

Patented June 15, 1920.

UNITED STATES PATENT OFFICE.

CHARLES HENRY PRAY, OF LOS ANGELES, CALIFORNIA.

FIRE-ESCAPE.

1,343,642.

Specification of Letters Patent. Patented June 15, 1920.

Application filed September 4, 1919. Serial No. 321,586.

To all whom it may concern:

Be it known that I, CHARLES H. PRAY, a citizen of the United States, residing at Los Angeles, county of Los Angeles, State of California, have invented a new and useful 5 Fire-Escape, of which the following is a specification.

My invention relates to fire escapes of the type usually forming a permanent part of 10 the building structure to which it is applied and has more particular relation to the so-called counterbalanced ground ladder type.

The object of the invention is to provide 15 a fire escape having second and third floor platforms with a permanent connecting ladder and a counterbalanced ground ladder slidable on the permanent ladder and latched in normal elevated position with the rings of both ladders horizontally alined 20 and positioned in close proximity to each other to form relatively wide steps.

Another object is to provide a supporting 25 latch for the slidable ground ladder accessible only from the second floor platform.

With these and other incidental objects 30 in view the invention consists of certain novel features of construction and combinations of parts, the essential elements of which are recited in the appended claims 35 and a preferred form of embodiment of which is hereinafter more fully described in connection with the accompanying drawings forming a part of this specification.

In the drawings corresponding reference 40 characters designate corresponding parts throughout the several views, of which:

Figure 1 is a front elevation of my improved fire escape as applied to a building, showing the ground ladder in normal ele- 45 vated position.

Fig. 2 is a side elevation thereof.

Fig. 3 is a similar side elevation showing the ground ladder in lowered position.

Fig. 4 is a bottom plan view of the sec- 45 ond floor platform.

Fig. 5 is a plan section on line x^5-x^5 of Fig. 1.

Fig. 6 is a detail section on line x^6-x^6 of Fig. 5.

50 In the drawings A designates the lower platform positioned adjacent a second story window of the building and hereinafter termed the second floor platform. B designates an upper platform hereinafter termed 55 the third floor platform. Each platform is secured to the building in the usual manner

and is provided with the usual guard rail 1 and open hatchway 2.

The supporting framework of each plat- 60 form includes a pair of parallel horizontal beams 3-4, extending outwardly from the building in alinement with the opposite sides of the hatchway.

A stationary ladder C is positioned be- 65 tween the two platforms with the terminal ends of its side rails 5-6 secured to the beams 3-4 of each platform.

A vertically movable ground ladder D is positioned closely adjacent the ladder C with its vertical side rails 7-8 in overlap- 70 ping engagement with the outer sides of the side rails 5-6 of the ladder C. The upper end of the ladder D is retained in close sliding engagement with the ladder C by a pair of retaining plates 9 which are 75 attached to the upper ends of the side rails 7-8 and are bent over the rear edges of the side rails 5-6 of the ladder C.

The ladder D slides in vertical guide 80 grooves 10-11 which are formed by plates 12-13 secured to the outer sides of the beam 3-4, and said ladder is normally latched in elevated position by a slidable latch 15 which is supported in a housing 16 secured to the plate 12. Said latch is 85 adapted to be translated horizontally to close the bottom of the groove 11 in which the movable ladder slides, the side rail 8 thereof resting on the latch, as a supporting abutment, which is in normal elevated posi- 90 tion. The latch 15 has an upturned flange 17 provided with a notch 18 adapted to be engaged by the lower end of an operating lever 19. Said lever is pivoted at 20 and extends upwardly through an opening in 95 the floor of the platform.

Means are provided for counterbalancing the ground ladder D, such means comprising a weight 21 slidable on a pair of vertical rods 22-23 extending between and at- 100 tached to the platforms A and B. Ropes or cables 24-25 are attached to opposite sides of the weight and each cable extends upwardly over a pair of sheaves 26-27 journaled upon the framework of the plat- 105 form B and downwardly to a point of attachment to the ladder D.

The construction provides a simple and practical fire escape comprising a pair of closely nested ladders, one stationary and 110 the other slidable thereon with the slidable ladder normally supported with the

rungs of both ladders relatively horizontally alined and positioned in close proximity to each other to provide a wide step.

I claim:

- 5 1. A fire escape comprising two relatively spaced stationary platforms and an intermediate stationary vertical ladder, a 35
slidable ground ladder, means for retaining said ground ladder in close sliding engagement with the stationary ladder, counter-balance means connected to the ground ladder, and manually operated means normally supporting the ground ladder in elevated position.
- 10 2. A fire escape comprising two relatively spaced platforms and an intermediate stationary vertical ladder, vertical guide rods intermediate of and secured to the platforms, a counterbalance weight 40
slidable on said rods, a ground ladder, means retaining the ground ladder in close sliding contact with the stationary ladder, cable 45
sheaves journaled on the upper platform, cables secured to the weight and to the
25 ground ladder and passing over the sheaves, and means carried by the lower platform
for normally supporting the ground ladder in elevated position and movable to release
said ladder.
- 20 3. A fire escape comprising an upper and
a lower platform having relatively alined
open hatchways, the lower platform hav-

ing opposed vertical grooves, a vertical stationary ladder secured at opposite ends to the upper and lower platform respectively, 35
a vertically movable ground ladder slideable in said grooves, means for guiding the upper end of the ground ladder relative to the stationary ladder, counterbalance means connected to the ground ladder and a horizontally 40
movable latch normally closing the bottom of one groove and forming a supporting abutment for the ground ladder.

4. A fire escape comprising an upper and a lower platform having relatively alined 45
open hatchways, the lower platform having opposed vertical grooves adjacent the hatchway, an intermediate stationary ladder, the upper ends of the side rails of said ladder being secured to the upper platform and the 50
lower ends of said side rails secured to the lower platform adjacent the vertical grooves, a ground ladder slideable in said grooves, counterbalance means connected to the ground ladder and a manually operated 55
means normally closing the lower end of one of the grooves and supporting the ground ladder in elevated position.

Signed at Los Angeles, California, this
7th day of August, 1919.
